UNITED STATES PATENT OFFICE.

HERBERT M. DAWLEY, OF BUFFALO, NEW YORK, ASSIGNOR TO THE PIERCE-ARROW MOTOR CAR COMPANY, OF BUFFALO, NEW YORK.

DESIGN FOR A VEHICLE-LAMP.

41,706.

Specification for Design.

Patented Aug. 22, 1911.

Application filed May 31, 1911. Serial No. 630,489. Term of patent 14 years.

To all whom it may concern:

Be it known that I, HERBERT M. DAWLEY, a citizen of the United States, residing at Buffalo, in the county of Erie and State of New York, have invented a new, original, and ornamental Design for Vehicle-Lamps, of which the following is a specification.

The accompanying drawing represents in Figure 1 a front elevation, in Fig. 2 a side elevation and in Fig. 3 a plan view of a vehicle lamp embodying the design.

The following are the characteristic features of the design: The lamp has a spherical body and a ventilator above the body

which is of polygonal shape in cross section, and is surmounted by a cap, also of polygonal cross section, having faces of compound curvature. Below the spherical body and connected thereto by a reduced waist portion is a cup-shaped oil font.

I claim:

The ornamental design for a vehicle lamp, as shown and described.

HERBERT M. DAWLEY.
